UNITED STATES PATENT OFFICE.

JAMES A. AMBLER, OF NATICK, MASSACHUSETTS.

BOOT-TREE.

SPECIFICATION forming part of Letters Patent No. 249,867, dated November 22, 1881.

Application filed October 17, 1881. (No model.)

To all whom it may concern:

Be it known that I, JAMES A. AMBLER, of Natick, Middlesex county, State of Massachusetts, have invented an Improvement in Boot Trees, of which the following description, in connection with the accompanying drawings, is a specification.

This invention consists in a boot-tree having an independent metal shield to more or less cover the front or knee piece of the tree, combined with a foot hinged to the said shield, preferably composed of sheet metal.

Figure 1 represents, in side elevation, a boot-tree containing my improvements; Fig. 2, a 15 sectional detail, showing the foot-piece swung back on its hinge or pivot; Fig. 3, a section on the dotted line x x , Fig. 2. Fig. 4 is a rear side elevation of part of the foot-piece and its connected metal shield; and Fig. 5 a front 20 elevation, showing the junction of the shield and foot.

The front a and back b of the tree may be of any usual construction, and may be composed either of wood or of cast metal, made 25 hollow for the reception of hot air, as may also be the foot c , to thus permit all parts of the tree to be heated, as provided for in patents already issued to me.

In trees as usually made the foot-piece is 30 connected with the front piece by means of a hook, which, at the proper times, is acted upon to cause the hook to be operative and confine the foot. In this my invention I dispense with such hook and attach the foot by a hinge or 35 joint, e , directly to a short block or section, a^2 , which abuts against the lower end of the front piece of the tree, the said section a^2 serving as the base or holder for the lower end of a shield,

f , (shown as a metal plate,) curved and fitted closely to and so as to cover the outer face of 40 the front piece, a , for more or less of its length. The male part 2 of the joint e is so shaped or tapered that its portion of greatest diameter falls just within the surface of the top of the foot-piece c , thus obviating a space, slot, or 45 crack at the junction of the foot and block or plate which might produce a mark or crease on the leather at the instep of the boot.

The tree may be expanded and contracted in any usual way. When contracted the operator, as he grasps the foot of the boot to draw it from the tree, at the same time draws the foot e of the tree from the front and back pieces, the metal piece f also coming off from 50 the front piece.

By forming the hinge or joint as described, and employing the shield f , the front of the boot leg and instep may be treed and finished 55 perfectly smooth.

The portion a^2 may be made of metal and be 60 integral with or attached to the shield f .

The shield and foot may be easily taken from the boot when they have been drawn from the front and back parts, as stated.

I claim—
65 The combination, with the front and back parts of a boot-tree, of a shield and foot hinged thereto, substantially as described.

In testimony whereof I have signed my name to this specification in the presence of two 70 subscribing witnesses.

JAMES A. AMBLER.
